UNITED STATES PATENT OFFICE.

CHARLES MATTHEWS MANLY, OF NEW YORK, N. Y.

VARIABLE-SPEED GEAR.

1,266,606.

Specification of Letters Patent.

Patented May 21, 1918.

Application filed November 2, 1908, Serial No. 525,925. Renewed October 2, 1917. Serial No. 194,417.

To all whom it may concern:

Be it known that I, CHARLES M. MANLY, a citizen of the United States, and resident of New York city, in the county of New York and State of New York, have invented certain Improvements in Variable-Speed Gears, of which the following is a specification.

My invention relates to improvements in variable speed gears or transmitting mechanisms of the class shown and described in my Letters Patent No. 710,485, dated October 7, 1902, and No. 801,097, dated October 3, 1905, in which a pumping device and a motor operated by fluid delivered from the pump are interposed between a prime mover or driving member and a driven device, whereby the driven member or device may be caused to operate at any and all speeds in both directions with a torque inversely proportional to its speed, without requiring changes either in the speed, direction of rotation, or power of the prime mover.

One object of my invention is to provide improved, simple and effective means in such mechanism for varying at will the velocity ratio of the driven member to the prime mover; a further object is to provide means whereby, when the pump and motor shafts are rotating in the same direction at substantially the same speed, the said shafts may be locked together and when it is desired that they cease to rotate at equal speeds they may be unlocked.

With these and other objects in view, my invention consists of an improved speed gear or transmitting mechanism embodying a pump driven from any external source of power, a motor connected to the pump by a fluid and adapted to be connected to a driven device or member, with means for adjusting the relative capacities of the pump and the motor, as hereinafter more particularly pointed out in the claims; and it further consists in means for locking together the pump and the motor when they are rotating at the same speed in the same direction, and finally in the novel construction and details hereinafter described, with reference to the accompanying drawings, and more particularly pointed out in the claims.

In the drawings, illustrating a preferred form in which my invention may be carried out:

Figure 1 is a top plan view of one form of the mechanism;

Fig. 2 is an enlarged longitudinal sectional view on the line 2—2, Fig. 1, looking in the direction of the arrows;

Fig. 3 is a transverse sectional view on the line 3—3, Figs. 1 and 2, looking in the direction of the arrows, with certain parts in elevation;

Fig. 4 is a transverse sectional view on the broken line 4—4, Figs. 1 and 2, looking in the direction of the arrows, with certain parts in elevation;

Fig. 5 is a transverse sectional view on the line 5—5, Figs. 1 and 2, looking in the direction of the arrows;

Fig. 6 is a sectional view on the line 6—6, Fig. 5, looking in the direction of the arrows;

Fig. 7 is a diagrammatic illustration of certain valves and connections of the control mechanism, hereinafter more particularly referred to;

Fig. 8 is an enlarged sectional view on the line 8—8, Fig. 5, looking in the direction of the arrows;

Fig. 9 is a similar view on the line 9—9, Fig. 5, looking in the direction of the arrows;

Fig. 10 is a similar view on the line 10—10, Fig. 5, looking in the direction of the arrows;

Fig. 11 is a detailed sectional view herein-after referred to;

Fig. 12 is an enlarged end elevation of Fig. 1 viewed from the left hand end;

Fig. 13 is a top plan view of a slightly modified form of the mechanism shown in Fig. 1;

Fig. 14 is a longitudinal sectional view on the line 14—14, Fig. 13, looking in the direction of the arrows;

Fig. 15 is an end elevation of Fig. 13 viewed from the left hand end; and

Figs. 16 to 19 are detail views hereinafter described.

Referring now to the drawings, in which the same reference characters relate to the same or corresponding parts in all the views, the numeral 18 indicates a casing in which is journaled, by means of two ball bearings 20 at the left hand side of Fig. 2, the pump cylinder element 22 consisting of a cylindrical tubular hub 24 in the interior of which is formed a valve chamber 26, while radiating from the hub 24 are nine hollow cylinders 28, Fig. 3, here shown as equidistantly spaced. Slidably mounted in each of the

cylinders 28 are pistons 30 connected at their outer ends by means of the bolts 32 to cross heads 34, which bolts pass through the holes 36 in the ends of the said cross heads 34 slightly larger than the bolts 32 to prevent lateral play of the cross head to prevent binding of the piston. The cross heads 34 are here shown as of tubular form slidably mounted on the exterior surface of the cylinders 28, while formed on each cross head at diametrically opposite points are the two cross head pins 38. Journaled on each cross head pin 38 by means of the balls 40 are rollers 42, which are retained in their proper position on the cross head pins by means of the rivets 44, journaled in the holes 46 in the said cross head pins, said pins being so positioned that the pins do not pass beyond the outer ends of the cylinders when the pistons are reciprocated, as hereinafter described.

Mounted in the casing 18, Figs. 2 and 3, is a crank element 48, on which are formed, at diametrically opposite points, the two adjusting heads 50 and 52, the head 50 with its encircling sleeve 54 being slidably mounted in the supporting arm 56 of the casing 18, and the head 52 with its encircling sleeve 58 being slidably mounted in the supporting arm 60 of the casing 18. The said crank element 48 is thereby transversely displaceable, so that its center may be adjusted to coincide with the center of the valve chamber 26, or to be eccentric to the said center on either side of the vertical line 2—2, Fig. 3.

Mounted in the crank element 48 are two circular rings or tracks 62 on which the cross head rollers 42 are adapted to roll when the cylinder element 22 is rotated, the rollers 42 being compelled to remain in contact with the tracks 62 by means of the guard flanges 64 of the crank element 48. Connected to the left hand end (Fig. 2) of the cylinder element 22 by means of the pin 66 is the driving head 68 of the driving shaft 70, the latter being journaled in the hub 73 of the casing 18 through which it passes to the outside for connection to any suitable driving device or power generator.

Mounted in the valve chamber 26 of the cylinder element 22 is the valve element 74 on the left hand end of which is formed the valve head 76. Formed on the right hand end (Fig. 2) of the valve element 74 is a valve head 77 which projects into the interior of the valve chamber 27 of the motor cylinder element 23, the latter by means of its hub 25 being journaled through the two ball bearings 21 in the casing 18. Radiating from the cylinder element 23 are nine, or any other suitable number, of motor cylinders 29, Fig. 4. Slidably mounted in each of the cylinders 29 are pistons 31 connected by the bolts 33 through the holes 37 to the cross heads 35. Journaled on the two cross

head pins 39 of each cross head by means of the balls 41 are cross head rollers 43 held thereon by the rivets 45 and which roll on the circular tracks 63 when the cylinder element is rotated, the tracks 63 being mounted in the two rings 49 which here constitute the motor crank element and which are in turn fixedly mounted in the casing 18; the center of the said circular tracks is, however, eccentrically placed with reference to the center of the rotary cylinder element 23, as clearly shown in Fig. 4. Formed on each of the two rings 49 of the motor crank element are inner annular flanges 65 which keep the rollers 43 from leaving the tracks 63 when the cylinder element 23 is not rotating. Connected to the right hand end of the hub 25 of the cylinder element 23, by means of the pin 67 and its driving head 69, is the driven shaft 71, which is journaled in the hub 73 of the casing 18 through which it passes for connection to any driven device or member.

Formed in the pump valve head 76 of the valve element 74, Figs. 2 and 3, are the two diametrically opposite main ports 86 and 88 respectively, which are separated from each other by the bridges 90 and 92. When the driving shaft 70 is rotated in the direction of the arrow shown in Fig. 2 (the cylinder element 22 rotating in a clockwise direction, as viewed in Fig. 2) the port 86 becomes the ingress port and the port 88 the egress port when the crank element 48 is in the position shown in Fig. 2 with its center eccentric to, and to the right of, the center of the valve element 74. Any fluid which is in the port 86 will then be free to pass therefrom through the cylinder ports 82 of the pump cylinders 28 when the said cylinders are rotating above the horizontal median line of Fig. 3, the bridges 90 and 92 being of a circumferential length equal to the circumferential length of the cylinder ports 82, the passage of fluid from the ingress port 86 to the cylinders 28 beginning as soon as the center of the cylinders passes the horizontal median line and continuing through 180 degrees of rotation until the center of the cylinders is again coincident with the horizontal median line. Any fluid which is in the cylinders 28 will be free to pass therefrom into the egress port 88 as soon as each cylinder in its rotation passes the horizontal median line and continuing through 180 degrees of rotation below the said line until the center of the cylinder is again coincident with the horizontal median line, and such fluid passed out of the cylinders 28 will be received into the egress port 88.

Formed in the body of the valve element 74 on the upper side of the horizontal median line, Fig. 3, are three ingress passages 84, which terminate at the left end, Fig. 2, in the ingress port 86 and at the other end in the 130

main port 87 of the motor valve head 77, and formed in the valve element 74 below the horizontal median line thereof are the three egress passages 85, terminating at the 5 left end in the port 88 and at the other end in the main port 89 of the said motor valve head 77. Separating the main ports 87 and 89 in the motor valve head 77 are two diametrically opposite bridges, one of which 10 91, is shown in elevation in Fig. 2, the other one which is diametrically opposite not being shown, as the valve head 77 is here shown as similar in all respects to the valve head 76, the location of the bridges of which 15 has been previously explained. With the eccentricity of the rings 49 of the motor crank element on the left hand side of the vertical median line through the valve element 74, as shown in Fig. 4, any fluid delivered from the pump cylinders 28 through 20 the egress port 88 and egress passages 85 to the main port 89 of the valve head 77 will be free to pass through the said port 89 and the motor cylinder ports 83 into the motor 25 cylinders 29 whenever the cylinders are below the horizontal median line of Fig. 2, and will there act against the pistons 31, thereby causing them through their cross heads 35, to force the rollers 43 against the 30 eccentric tracks 63, thus causing the cylinder element 23 to revolve in a clockwise direction, as viewed in Fig. 4. As the motor cylinder element 23 is thus rotated the fluid which is in the cylinders 29 will be forced 35 therefrom, whenever the said cylinders are rotating above the horizontal median line, and will pass into the port 87 and through the passages 84 to the ingress port 86 of the valve head 76, the fluid thus being caused 40 to circulate in a continuous circuit from the pump cylinders to the motor cylinders and back again.

Formed in the outer surface of the pump valve head 76, (Fig. 2), and diametrically opposite the egress port 88, are two recesses 45 94 and 96, respectively, each of a circumferential length equal to the said port 88, and each of an axial width equal to one-half the axial width of the port 88, and symmetrically spaced with reference thereto, so that the effect of any fluid pressure between the port 88 and the valve chamber 26 tending to 50 force the valve head 76 toward the opposite side of the valve chamber 26 will be balanced by permitting the same fluid pressure to pass from the port 88 through the hole 98 into the recess 94, and through the hole 100 into the recess 96, to act between the said 55 recesses and the valve chamber 26, and on account of such balancing action, I have, 60 therefore, designated these recesses 94 and 96, respectively, as balance ports. Similarly the valve head 76 is provided on the opposite side with the two balance ports 102 and 65 104 connected by the holes 106 and 108 with

the port 86 whereby the effect of fluid pressure in the said port 86 will be balanced by fluid pressure in the balance ports 102 and 104. The holes 100 and 106 and the holes 98 and 108 do not connect, as they are in different planes in the body of the valve. In a similar manner the motor valve head 77 is provided with the balance ports 95 and 97 connected by the holes 99 and 101 with the port 89, and the balance ports 103 and 105 connected by the holes 107 and 109 with the port 87.

By means of the ball bearings 20, the balls of which roll in grooved tracks in the outer and inner rings of the said bearings, and the inner rings of which abut against the shoulders 110 and 112 on the hub 24 of the cylinder element 22, the said cylinder element 22 is located both axially and radially with reference to the casing 18, and in a similar manner by means of the ball bearings 21 and the shoulders 111 and 113 on the hub 25 of the motor cylinder element 23, the said motor cylinder element 23 is also located both radially and axially with reference to the said casing 18, the space between the outer rings of the two inner ball bearings 20 and 21, respectively, being filled by the gimbal ring 80 which is prevented from turning with reference to the casing by means of the two pins 370, (Fig. 5) which are connected by threads to the casing 18 and pass through the two diametrically opposite holes 114 in the ring 80; these pins are prolonged toward the center and pass through the diametrically opposite holes 115 in the gimbal ring 79, and the pins 78 mounted in the two diametrically opposite holes 116 of the ring 79 are prolonged toward the center into the holes 117 in the lugs 118 formed on the valve element 74. The interior of the ring 79 is made slightly larger than the projecting lugs 118 of the valve element 74, and its outside diameter is made slightly smaller than the inside diameter of the ring 80, and the pins 78 and 370, respectively, are so mounted as to permit the said gimbal ring 79 to rock on them. The clearances between the ring 80 and gimbal ring 79 and valve element 74 permit the valve element 74 to have freedom of movement with reference to the casing 18, except rotation and endwise displacement with respect thereto, the valve element thus being permitted to find its own proper alignment with respect to the pump cylinder element 22 and the motor cylinder element 23, but being held from rotation and axial displacement by means of the said gimbal rings.

Formed on the valve element 74 is a boss 120 in which is provided a passage 121 connecting the ingress passages 84 of the said valve element 74 to the pipe 122 which passes through the holes 123 and 124 in the rings 79 and 80 respectively, and through 130

the plug 126 of the casing 18, connecting at its other end with the control valve block 127. Formed on the valve element 74 is another boss 128 in which is a passage 129 which connects the egress passage 85 with the pipe 130 which passes through the holes 131 and 132 in the rings 79 and 80, respectively, and through the plug 133 connecting at its other end with the said valve block 127.

10 Formed in the said control valve block 127 is a cylindrical valve chamber 134, which, by means of the port 135 is connected with the pipe 122 above described. Similarly the valve chamber 134 is connected to 15 the pipe 130 by means of the port 136. Mounted in the valve chamber 134 is a valve 137 comprising two heads 138 and 139, respectively, joined by the stem 140, and formed on the right hand end of the said 20 valve 137 is a stem 141 which passes through the plug 143, and on the outer end of which is mounted a yoke 142. Formed on the other end of the said valve 137 is a stem 144, which is slidably mounted in the plug 145 25 which closes the left hand end of the valve chamber 134. With the valve 137 in the position shown in Fig. 5, passage of fluid from the pipe 122 to pipe 130 is prevented by the valve head 139, but if the said valve 30 137 is moved toward the right a distance equal to the actual length of the valve head 139, the said valve head will begin to uncover the port 135 and further movement of the said valve to the right will permit fluid 35 to pass from the pipe 122 to the said pipe 130, and I, therefore, designate the said valve 137, a by-pass valve. In order to balance the said by-pass valve 137 so that fluid pressure introduced into the valve chamber 134 through the pipe 130 and port 136 will 40 not act to displace the said valve from the position shown or prevent its easy operation by manual exertion of the operator, I provide holes or passages, not shown, in the 45 body of the said valve leading from one end thereof to the other, so that whatever fluid pressure is in one end of the valve chamber has free access to the other end thereof.

Formed in a lower horizontal plane in 50 the said valve block 127 (as shown in section in Fig. 6) is a valve chamber 146, the two ends of the said valve chamber 146 being of the same diameter of bore, while formed near the center of length of the 55 said chamber is a reduced bore 147. Mounted in the said valve chamber is a valve 148 comprising three heads, the two outer ones 149 and 150 being of the same diameter and fitting the bore of the valve 60 chamber 146, while the central valve head 151 is of a reduced diameter fitting the reduced bore 147. The valve chamber 146 is closed at its two ends by the plugs 152 and 153 respectively, and mounted between 65 the plug 152 and the valve head 149 is a

spring 154, while between the valve head 150 and the plug 153 is a spring 155, which, for reasons hereinafter stated, is of such a length compared with the spring 154 that the said valve 148 tends to stay in the position shown in Fig. 6, unless displaced therefrom by fluid pressure introduced in the said valve chamber by means herein-after described.

70 Formed in the valve block 127 is a passage 75 156 which connects at its lower end with the right hand end of the valve chamber 146 and to the left of the valve head 149, while the upper end of the said passage 156 connects with the port 135 of the by-pass valve 80 chamber 134 as shown by the dotted lines in Fig. 5 and in section in Fig. 8.

Formed in the valve block 127 is another 85 passage 157 (Figs. 5 and 10) which similarly connects at its lower end with the left hand end of the valve chamber 146 to the right of the head 150 and at its upper end with the valve chamber 134 and thereby with the port 136. By these means any fluid pressure existing in the pipe 122 will be free to 90 pass through the port 135, passage 156, into the right hand end of the valve chamber 146 where it will act, due to the difference in size of the valve heads 149 and 151, respectively, to force the valve head 149 toward 95 the plug 152, and if the fluid pressure so introduced is sufficient it will thereby cause the central valve head 151 to move to the right of the port 158, formed at the center of the reduced valve bore 147, and thereby 100 connect the port 158 with the passage 157 which, in turn through the valve chamber 134, and port 136, is connected with the pipe 130 and thereby with the passages 85. Similarly if fluid pressure pass from 105 the passage 85 through the pipe 130, port 136, valve chamber 134 and passage 157 into the valve chamber 146, and if such fluid pressure so introduced therein is greater than the fluid pressure introduced 110 through the passage 156, as above described, the said fluid pressure introduced through the passage 157 will act to cause the valve head 151 to move to the left of the port 158, as shown in Fig. 6, thereby connecting 115 the port 158 with the passages 84 of the valve 74 through the passage 156, port 135, and pipe 122, above described. It is thus seen that the said valve 148 automatically acts to connect the port 158 with the low 120 pressure side or ingress passages of the said valve 74, whichever passages happen to be the ingress ones at the time, and I therefore designate it the low pressure circuit valve.

125 Formed in the same horizontal plane in the said valve block 127 is a valve chamber 160 closed at its two ends by the plugs 161 and 162, and mounted therein is a valve 163 comprising three heads 164, 165, and 130

166, respectively, of the same diameter. Formed in the valve head 164 are passages 167 which connect the space between the valve heads 164 and 165 with the space between the valve head 164 and the plug 161, and mounted between the said valve head 164 and the plug 161 is a spring 168. Similarly in the valve head 166 are passages 169, which connect the space between the valve heads 166 and 165 with the space between the valve head 166 and the plug 162, and mounted between the valve head 166 and the plug 162 is a spring 170 which is of equal strength to the spring 168 so that the valve 163 tends to remain in the position shown in Fig. 6, unless displaced therefrom by means hereinafter described.

Formed in the valve block 127 is a passage 171 which connects at its lower end with the valve chamber 160 between the valve heads 165 and 164, while its upper end connects with the valve chamber 134, and thence with the port 135, as more clearly shown in Fig. 8. Formed in the valve block 127 is a similar passage 172 connecting at its lower end with the valve chamber 160 between the valve heads 165 and 166, while its upper end connects with the valve chamber 134 to the left of the valve head 139 and thence through the port 136 with the pipe 130, as more clearly shown in Fig. 10.

Formed in the valve chamber 160 at its center of length and under the valve head 165, as shown in Fig. 6, is a port 173, which when there is no fluid pressure in the valve chamber 160, is automatically cut off from communication therewith, but, when fluid pressure is introduced in the said valve chamber 160 through the passage 171 or the passage 172, the said port is automatically connected to whichever of the said passages contains the higher fluid pressure, as the said fluid pressure acting in the said valve chamber 160 forces the valve head 165 toward the opposite end of the chamber. It is thus seen that the valve 163 acts to connect the port 173 through the passage 171 or 172 with whichever side of the valve element 74 is at the time the high pressure side, and I, therefore, designate the said valve 163 the high pressure circuit valve.

Formed in the valve block 127 parallel to the valve chamber 160 is a passage 174 which by means of the passage 175 is connected with the passage 176, as more clearly seen in Fig. 10. The said passage 176 connects at its right hand end, Fig. 5, with the chamber 177, closed at its outer end by the plug 178. Mounted in the chamber 177 is a valve 179, the left hand end 180, being slidably mounted in the passage 176, previously described. Formed on the left hand end of the plug 178 is a stem 181 which telescopes into the bore 182 formed in the valve

179, the said valve 179 being slidably mounted on the said stem 181. Provided between the flange 183 on the valve 179 and the plug 178 is a spring 184 acting between the said flange and plug to keep the valve 179 in the position shown in Fig. 5. Formed in the end 180 of the valve 179 is a passage 185 connecting the passage 176 with the bore 182 of the valve 179, the diameter of the passage 176 being slightly greater than the diameter of the bore 182 whereby fluid pressure existing in the passage 176 will tend to force the valve 179 toward the right. As the said passage 176 is connected through the passages 174 and 175 with the port 173 (Fig. 6) and as the port 173 is automatically connected by the valve 163 with the high pressure side of the valve element 74, it is thus seen that any high pressure existing in the valve element 74 will at all times be free to act in the passage 176 to force the valve 179 toward the right, and as the forcing of the valve 179 toward the right when carried sufficiently far will connect the passage 176 with the chamber 177, and as the chamber 177 is connected by means of the passages 186 (Fig. 9) with the low pressure circuit valve chamber 146 through the port 158, and thereby with the low pressure side of the valve element 74, I therefore designate the said valve 179 a safety valve.

Formed near the bottom of the valve block 127 (Fig. 5) is a valve chamber 187, in which is mounted a valve 188 comprising four heads 189, 190, 191 and 192, respectively, while projecting from the right hand end of the valve head 189 is a stem 193 provided with a reduced neck 194 which passes through the hole 195 in the cross head 196, the said cross head 196 being slidably mounted on the prolongation 197 of the valve chamber 187 and connected to the valve stem neck 194 by the nut 198. Formed on the cross head 196 are two diametrically opposite cross head pins 199 the object of which will be explained later. Formed in the valve chamber 187 between the valve heads 189 and 190 is a passage 200 to which is connected the pipe 201. Formed to the left of the passage 200 and under the valve head 190 is a port 202 to which is connected the pipe 203, and under the valve head 191 is a port 204 to which is connected the pipe 205; the object of the pipes 201, 203 and 205 (shown broken in Fig. 5) is explained hereinafter.

Formed in the upper side of the valve chamber 187 between the valve heads 189 and 190 is a passage 206 connecting with the passage 207, (shown dotted in Fig. 5 and in cross section in Figs. 8, 9, and 10), the said passage 207 connecting near its other end with the passage 208 which enters the upper side of the valve chamber 130

187 between the heads 191 and 192, thus joining the two portions of the valve chamber together. Connected with the passage 207 is a passage 209, (shown dotted in Fig. 5 and in cross section in Fig. 9), which connects with the port 158 of the low pressure circuit valve chamber 146, the said port 158 being connected by the passages 186 with the low pressure side of the safety valve chamber 177, previously described. Connected with the valve chamber 187 between the valve heads 190 and 191 is a passage 210 (Fig. 9) which connects with the high pressure circuit valve chamber 160 in the port 173, the said port 173 being connected by the passage 212 with the passage 174, which is further connected by the passage 175 with the passage 176 (as shown in Fig. 10), which forms the high pressure side of the safety valve chamber heretofore described.

Referring now to Fig 3, it will be readily seen that when the crank element 48 is eccentric to the center of rotation of the cylinder element 22, rotation of the said cylinder element 22 will cause the cross head rollers 42 to roll on the tracks 62, thereby causing the cross heads 36 to move from their innermost position with respect to the center of the said cylinder element 22 to their outermost position during 180 degrees motion above the horizontal median line when the cylinder element 22 is rotated in a clockwise direction, as viewed in Fig. 3, provided the center of the said crank element 48 is to the right of the vertical median line; and when the center of the said crank is eccentric to and to the left of the center of rotation of the said cylinder element 22, the cross heads 36 will move in a reverse direction or from their outermost position to their innermost position during the corresponding angular motion. Similarly the cross heads move from their outermost position to their innermost position during 180 degrees motion below the center line when the center of the crank element 48 is to the right of the vertical median line, and in the reverse direction when the center of the said crank element 48 is to the left of the vertical median line. Since the pistons 30 are so connected to their respective cross heads 36 as to move with them, the said pistons 30 will be reciprocated inside the bore of the cylinders 28 in unison with the reciprocation of the cross heads on the exterior of the said cylinders, and consequently any fluid in the ingress port 86 will be drawn through the cylinder ports 82 into the bore of the cylinders while the said cylinders are rotating in a clockwise direction above the horizontal median line, and correspondingly any fluid so drawn into the bore of the cylinders 28 will be forced therefrom into the egress port 88 while the cylinders are rotat-

ing below the horizontal median line. The mechanism described thus acts as a pump to draw fluid in from the port 86 and force it out through the port 88, the amount of fluid drawn in and forced out during each revolution of the cylinders being dependent on the degree of eccentricity of the crank element 48 with respect to the center of rotation of the cylinder element 22. When the crank element 48 is concentric with the center of rotation of the cylinder element 22 the rotation of the said cylinder element 22 will produce no reciprocation of the pistons 30 and consequently no fluid will be drawn in or forced out of the said cylinders. When the center of the crank element 48 is to the left of the center of rotation of the cylinder element 22, as viewed in Fig. 3, the function of the ports 86 and 88, respectively, will be reversed, fluid being drawn in through the port 88 and forced out through the port 86, and in order to control both the amount of fluid so drawn in and forced out of the said cylinders and also the function of the ports 86 and 88, I provide means for adjusting the center of the crank element 48 with respect to the center of rotation of the cylinder element 22. Such adjustment might be effected by means of a screw and nut, the screw being connected with the crank element 48 and the nut connected with the casing 18 or several other equally simple means might be employed, but I prefer to effect this adjustment by the means which I will now describe.

Formed in the adjusting head 52 of the crank element 48 is a chamber 215 in which is mounted a shell 216, and connected to the said adjusting head 52 by means of the threads 217 is a rod 218 which passes through the hole 219 in the base of the shell 216, the said rod 218 having a collar 220 which is drawn against the base of the said shell 216. Mounted in the supporting arm 60 of the casing 18 is a piston 221, which by means of the collar 222 and the nuts 223 is held securely against longitudinal motion with respect thereto, the said piston projecting into the cylinder 216. The rod 218 passes through the hole 224 in the piston 221, and formed in the piston 221 is a cavity 225 which is closed at its outer end by the plug 226, which is provided with the bore 227 through which the rod 218 passes. In assembling the pump, the piston 221 is inserted in the supporting arm 60 while the two halves of the casing are unattached, hence when the halves are drawn together by their connecting bolts, the collar 222 lies within an internal flange on the end of the arm 60. The clamping nuts 223 are then tightened up against the flange, holding the piston rigidly in place.

Formed in the rod 218 are radial holes 228 which connect with the axial hole 229, 130

connected at its other end with the radial holes 230, the said cavity and holes being provided so that any fluid introduced into the cavity 225 may freely pass therefrom into the space between the piston and the bottom of the cylinder, and any fluid in the latter space may freely pass in the reverse direction.

Formed in the piston 221 is a passage 231 which connects the cavity 225 with the pipe 203, shown broken in Fig. 3, and as connected to the port 202 at the bottom of the adjusting valve chamber 187 in Fig. 5.

Formed in the adjusting head 50 of the pump crank element 48 is a chamber 232 in which is mounted a shell 233. Mounted in the supporting arm 56 of the casing 18 is a piston 234 which by means of the collar 235 and the nuts 236 is held securely against longitudinal motion with respect thereto. Formed in the center of the piston 234 is a passage 237 which connects at its right hand end with the interior of the shell 233 and at its outer end with the pipe 205, shown broken in Fig. 3, but as connected to the port 204 of the adjusting valve chamber 187 in Fig. 5.

It has been previously explained that with the parts in the position shown in the drawings, when the pump cylinder element 22 is rotated in a clockwise direction as viewed in Fig. 3, fluid will be drawn from the passages 84 and port 86 in the cylinders 28 when the said cylinders are rotating above the horizontal median line, and such fluid will be forced out under pressure into the port 88 and passages 85 when the said cylinders are rotating below the horizontal median line. It has also been previously explained that when the center of the crank element 48 is on the left of the vertical median line in Fig. 3, and the cylinder element 22 is rotated in the same or clockwise direction, the port 86 and passages 84 and the port 88 and passages 85 mutually change their functions, the port 88 becoming the ingress port and the port 86 the egress port. It has also been explained that, by means of the pipes 122 and 130, fluid pressure from the passages 84 and 85 respectively, is led through the by-pass valve chamber 134 and the passages 171 and 172, respectively, to the high pressure circuit valve chamber 160 and through the passages 156 and 157 to the low pressure circuit valve chamber 146, and also how the high pressure fluid is thus, by means of the passage 210, always connected to the adjusting valve chamber 187 between the valve heads 190 and 191, and how the low pressure fluid by means of the passages 207, 206 and 208 is also connected to the said adjusting valve chamber 187 between the heads 189 and 190 and between the heads 191 and 192 respectively. It has also just been shown how the

pipe 203 connected the port 202 of the adjusting valve chamber 187 to the space between the adjusting piston 221 and the interior of the shell 216, and how the pipe 205 connects the port 204 with the space 70 between the piston 234 and the shell 233. In order to make these connections clear they are shown diagrammatically in Fig. 7 with the same numerals designating the same or corresponding principal parts. Referring 75 now particularly to Fig. 7, it will be readily seen that when fluid under pressure exists in the pipe 130 the said fluid pressure will pass through the passage 172 into the left side of the high pressure circuit valve chamber 160 forcing the valve 163 toward the right side of the chamber and thereby causing the head 165 to uncover the port 173 connected to the passage 210 leading to the high pressure section of the adjusting valve 80 chamber 187 between the heads 190 and 191. The high pressure fluid which enters the high pressure circuit valve chamber 160 is also free to pass through the passage 157 into the left side of the low pressure circuit 85 valve chamber 146, where acting between the two unequal valve heads 150 and 151 it causes the low pressure circuit valve 148 to be forced toward the left side of the chamber thus causing the valve head 151 to 90 move as to prevent high pressure fluid from being connected with the port 158 and passage 207. Such motion of the valve 148, however, connects the opposite side of the valve chamber 146 through the port 158 95 with the passage 207 and thus with the low pressure sections of the adjusting valve chamber 187 between the heads 189—190 and 191—192. Low pressure or suction fluid is thus free to pass from the passage 207 100 through the valve chamber 146, between the heads 149 and 151, through the passage 156, passage 171 and pipe 122 to the low pressure passages 84 of the valve element 74. Such movement of the low pressure circuit valve 148 also connects the pipe 122 105 with the passage 186 which leads into the low pressure side of the safety valve chamber 177, and it also connects the pipe 122 to the passages connected to the space between the adjusting valve heads 189 and 190 and the heads 191 and 192, respectively, 110 so that if the adjusting valve 188 is adjusted to the right, high pressure fluid between the heads 190 and 191 will pass through the pipe 203 and into the space between the shell 216 of the adjusting head 52 and the piston 221 attached to the supporting arm 60, thus 115 forcing the said adjusting head to the left and thereby causing fluid between the shell 233 of the adjusting head 50 and piston 234 attached to the supporting arm 56, equal in amount to the high pressure fluid introduced in the opposite chamber, to be forced out through the pipe 205 into the adjusting 120 125 valve chamber 187.

valve chamber 187 between the heads 191 and 192 and from thence through the passages 208, 207 and 209 into the right hand side of the low pressure circuit valve chamber 146, and from thence through the passage 156 into the right hand side of the high pressure circuit valve chamber 160, and thence through the passage 171 into the by-pass valve chamber 134, and thence through the pipe 122 into the ingress passages 84 of the valve 74. Similarly if high pressure exist in the pipe 122, the high pressure circuit valve 163 will be forced to the left, thus causing such high pressure to be connected to the high pressure side of the safety valve chamber 176 and also to the adjusting valve chamber 187 between the heads 190 and 191 and such high pressure will also act in the low pressure circuit valve chamber 146 to force the low pressure circuit valve 148 to the right and thus shut off communication between the passages 156 and 209, and low pressure will be free to pass from the adjusting valve chamber 187 between the heads 189 and 190 and the heads 191 and 192, respectively, through the passages 206, 208, 207 and 209 to the left hand side of the low pressure circuit valve chamber, and thence through the passage 157 to the left hand side of the high pressure circuit valve chamber 160, and thence through the passage 172 into the left hand side of the by-pass valve chamber 134, and thence through the pipe 130 into the main circuit passages 85, which in this case we have supposed to have become the ingress passages. It is thus seen that, by the above described means, fluid pressure derived from the high pressure side of the main fluid circuit connecting the pump and motor may be utilized for adjusting the eccentricity of the crank element 48 with respect to the center of rotation of the cylinder element 22. In order, however, to better control this fluid pressure adjusting mechanism, I provide means, which I will now describe, for causing the said adjusting mechanism to automatically cease to act when it has moved to a position indicated by the motion of an operator's control lever. Referring again to Fig. 7 and assuming fluid pressure to exist in the pipe 130, said pressure will by the means just described pass into the adjusting valve chamber 187 between the valve heads 190 and 191. If the pipe 130 is the high pressure pipe the pipe 122 will be the low pressure or suction pipe, and any fluid introduced into the adjusting valve chamber 187 between the heads 189 and 190 and the heads 191 and 192 will be free to pass into the low pressure pipe 122, and thence to the low pressure side of the main circuit. Connected to the outer end of the rod 218 is a lever 250 which by means of a pin 252 has a rocking connection therewith. Formed on one end of the lever 250 is a manual control handle 254 and between the said handle 254 and the pin 252 is a pawl 256 co-acting with a quadrant 258, mounted on the casing 18, the said pawl being manually releasable by means of the button 260, rod 262, and co-acting spring 264 normally holding the pawl into contact with the quadrant. The other end of the lever 250 has a rocking connection through the pin 266, with the valve stem 193 of the adjusting valve 188. If now the handle of the control lever 250 be moved to the left in Fig. 7, the adjusting head being relatively hard to move, the pin 252 will act as a fulcrum and cause the other end of the lever 250 to pull the adjusting valve 188 to the right, thereby causing the head 190 to uncover the port 202 permitting high pressure fluid between the heads 190 and 191 to pass through the port 202 and pipe 203 between the shell 216 of the adjusting head 52 and the piston 221 attached to the adjusting arm 60, thereby causing the adjusting head 52 and consequently the crank element 48 to move to the left. As soon as the adjusting head 52 begins to move under the action of the fluid pressure the lever 250 acts on the operator's hand, (or if the pawl 256 be in contact with the quadrant 258 then on the said pawl 256) as a fulcrum, and motion of the said adjusting head will cause the upper end of the lever 250 to be pulled to the left so that the adjusting valve 188 will also be carried to the left toward the position from which it has been displaced by the operator, and the valve head 190 will again cover the port 202 when the adjusting head 52 has moved to the position indicated by the extent of motion given to the handle of the lever 250 by the operator. Similarly, right hand motions by the operator of the lever 250 will cause the adjusting valve 188 to move to the left, thus causing the head 191 to uncover the port 204, and permitting high pressure fluid to pass between the shell 233 of the opposite adjusting head 50 and the piston 234 attached to the supporting arm 56, and such fluid pressure will cause right hand motion of the said adjusting head 50, which in turn will produce right hand motion of the adjusting valve 188 and cause the adjusting valve to close the port 204, when the said adjusting head 50 has moved to an extent proportionate to the extent of movement given to the lever 250 by the operator. From the previous description of the valves and connections in Fig. 7, it will be seen that if the pipe 122 be the high pressure pipe and 130 the low pressure one, high pressure fluid will be delivered to the same portions of the adjusting valve chamber 187 as just described when the pipe 130 was the high pressure pipe, and low pressure fluid will be free to pass from the same portions of the adjusting valve chamber 130.

ber 187 of the pipe 130. Furthermore, it is seen from Fig. 7 that if the pressure of the fluid in the high pressure pipe, whether the said pipe be 122 or 130, rise above the amount sufficient to raise the safety valve 179 against the action of the spring 184, such excess pressure will be relieved by the fluid passage from the high pressure side 176 of the safety valve chamber to the low pressure side 177, and such fluid passing through the said safety valve will, therefore, be merely by-passed from one side of the fluid circuit of the mechanism to the other side.

15 The preceding description of the operation of the control mechanism has been based on the diagrammatic view in Fig. 7 in which some of the details of the mechanism have been omitted for simplicity, but 20 where the essential details have been given with the same designating numerals as those of the corresponding parts in the views of the actual mechanism. The details of the actual mechanism which have been omitted 25 from the diagrammatic view will now be described. Referring more particularly to Figs. 1, 2 and 5, the rod 218 carries at its outer end the yoke 268 with which the control lever 250 has a rocking connection 30 through the pin 252. Instead of the end of the lever 250 being connected direct to the stem 193 of the adjusting valve 188, as shown in the diagrammatic view, Fig. 7, it is connected by the pin 266 to the double link 501 which is connected at its other end to the cross head pins 199, previously described, and thus to the said adjusting valve 188. Projecting from the quadrant 258 is a bracket 270 by means of which it 40 is connected to the casing 18.

When the crank element 48 is concentric with the center of rotation of the cylinder element 22, rotation of the said cylinder element produces no pressure in the main 45 fluid circuits, and movement of the adjusting valve 188 will not be accompanied by motion of the adjustable crank element 48, since there is no fluid pressure which can act to effect the adjustment. At this same 50 time there is also no force acting on the crank element 48 to displace it from its position of concentricity, and while fluid pressure (derived at other times when there is fluid pressure in the main fluid circuit) 55 might be stored in a tank to be used at this critical position, which is a method that I have practised in some forms of mechanism, yet I prefer in this mechanism to produce the necessary adjustment of the 60 crank element 48 through the point of concentricity by means of manual exertion, since the manual exertion required is comparatively small and tends to simplicity of construction. I have, therefore, provided 65 means whereby when the control lever 250

has been so moved as to cause the adjusting valve to open the ports permitting fluid pressure to pass to the adjusting mechanism and no fluid pressure exists to effect such result, the cross-head 196 on the tubular prolongation of the adjusting valve chamber 187 becomes a momentarily fixed fulcrum due to the ears 272 which project from the said cross-head 196 striking against the nuts 274 on the end of the studs 276 70 or against the shoulders 278 on the said studs 276, where they abut against the end of the valve block 127, the said studs passing parallel to the said valve block 127 and finally fastening into the main casing 80 18 and thereby serving to hold the said valve block 127 securely in its position. When the ears 272 of the cross-head 196 strike either the nuts 274 or the shoulders 278 any movement of the control lever 250 85 produced by manual exertion on the handle 254 will produce a corresponding movement of the rod 218 and consequently of the adjustable crank element 48, the port 158 of the low pressure circuit valve chamber being normally open owing to the spring 155: 90 being weaker than the spring 154 and consequently fluid from the adjusting chambers is free to pass out into the low pressure side of the main fluid circuit, thus 95 enabling the said crank element 48 to be moved to a position of eccentricity with respect to the cylinder element 22. Just as soon as the crank element 48 becomes eccentric, even to the slightest degree with respect to the rotating cylinder element 22, the rotation of the said cylinder element produces fluid pressure in one side or the other of the main fluid circuit and such fluid pressure is therefore immediately available 100 for use in effecting further adjustment of the crank element 48. Manual exertion on the part of the operator for performing adjustment is, therefore, required only for moving the crank element 48 105 through an infinitesimal distance at the position of concentricity.

The previous description of the mechanism has been based on the assumption that the main fluid circuits, including the cylinders of both the pump and the motor and all of the ports and passages of the adjusting mechanism are kept filled with fluid, which in practice is found to be difficult, unless some means be employed for returning to 110 the fluid connection the minute quantities of fluid which pass through the working joints into the interior of the casing, unless the said casing be filled with fluid. I prefer, however, not to fill the casing with an 115 incompressible fluid such as oil, which I prefer to use, as the rotation of the cylinder element through such a fluid produces considerable friction resulting in the loss of power or a reduction in efficiency of the 120 125 130

mechanism. While, therefore, the interior of the casing may be filled with the fluid, and if desired a reservoir at a higher level may be connected with the said casing so as to maintain it always full and thereby insure that the main fluid circuit will always be kept full by permitting the low pressure side of the fluid circuit to always be connected with the interior of the casing, yet I find it advantageous in practice to keep only a small amount of oil in the casing, such an amount as is necessary for a reserve supply to make up any leakages which occur from the connections outside of the casing, and I therefore employ a small auxiliary pump which I have termed a leakage pump, which runs whenever the driving shaft of the pump runs and is connected on its suction side with the bottom of the casing, and on its delivery side with the low pressure side of the main fluid circuit, so that the main fluid circuit is not only kept completely full of fluid but preferably at a pressure which is slightly in excess of atmospheric pressure in order to avoid cavitation in the pump, which might otherwise be caused by the rapid speed of reciprocation of the pump element. I have, therefore, shown at the left hand end of Fig. 2 a small gear pump 280, comprising the gear 282 rigidly mounted on its shaft 284, co-acting with the gear 286 rigidly mounted on its shaft 288, both of the said gears being housed in the projection 290 of the casing 18 in which one end 35 of their respective shafts is journaled. The shaft 284 of the gear 282 passes through the said casing 18 and carries on its other end a gear 292 connected thereto by the pin 294, the said gear 292 co-acting with the gear 296 mounted on the shaft 70 and connected thereto by the pins 298 which pass into the driving head 68. Fastened on the outer end of the projection 290 of the casing 18 by means of the screws 300 is a cap or cover 302 in which the outer ends of the shafts 284 and 288 are journaled. Referring more particularly to Fig. 12, which is an end elevation of Fig. 2, it will be seen that on the right hand side of the projection 290 of the casing 18 is a hollow boss 304 to which is connected the upper end of a pipe 306, the lower end of which enters the interior of the casing 18 near the bottom through the boss 308, the said pipe 306 being thus connected 55 with the suction side of the leakage pump 280 when the shaft 70 revolves in a clockwise direction, as viewed in Fig. 12, or in the direction of the arrow in Fig. 2. Formed on the casing 18, and to the left in Fig. 12 of the leakage pump, is a projection 310 which, from the broken section shown in Fig. 11, is seen to contain a chamber 312, covered at its outer end by a flanged cap 314, held by bolts 316 against the said projection 310, the outer end of the said cap

314 being closed by a threaded plug 318. The inner end of the chamber 312 connects with the reduced bore 320 which communicates with the interior of the casing 18. Formed in the projections 290 and 310 is a 70 passage 322 which connects the chamber 312 with the delivery side of the leakage pump, while on the opposite side of the chamber 312 is a boss 324 through which is formed a passage 326 which communicates at one 75 end with the said chamber 312 and at its other end with the pipe 201 which in Figs. 1 and 11 is shown broken, but which is supposed to be continuous from the chamber 312 to the port 200 of the valve block 127 of 80 Fig. 5, where it is there shown broken. In the previous description the port 200 was seen to be always connected to the low pressure side of the main fluid circuit. Any fluid delivered from the leakage pump to 85 the said pipe 201 will, therefore, be carried to the low pressure side of the main fluid circuit no matter which side is the low pressure side, but since the leakage pump runs continuously and would, therefore, tend to 90 raise the pressure in the low pressure side of the main fluid circuit above the small back pressure which it is desired to carry, the chamber 312 is provided with a low pressure relief valve 328 which maintains the 95 back pressure in the main fluid circuit at a fixed amount previously determined. The said low pressure relief valve 328 is provided at one end with a head 330 which is slidably mounted in the reduced bore 320. Formed on the stem of the said valve 328 are 100 projecting lugs 332 which project from the said stem sufficiently to prevent the said valve 328 from passing too far through the reduced bore 320. Formed on the valve 328 at a point intermediate of its length are 105 larger projecting lugs 334 and between one side of the said lugs 334 and the shoulder 336 of the chamber 312 is a spring 338 while between the other side of the lugs 334 and the cap 318 is a similar spring 340. Any fluid pressure introduced into the said chamber 312 will act on the valve 328 and cause the head 330 to move toward the interior of the casing 18, and when the said pressure is great enough the said valve head will move sufficiently far to permit fluid to pass through the slots 342 in the valve head 330 into the interior of the said casing 18, the pressure sufficient to cause such a result 110 being dependent on the stiffness of the springs 338 and 340.

Since in some conditions of use of the mechanism it is desirable to be able to revolve the pump without revolving the motor, 125 or to permit the motor to revolve without revolving the pump, I have provided the by-pass valve chamber 134 with its by-pass valve 137, Fig. 5, and connected to the valve stem 141 at its outer end is the yoke 130

142, Fig. 1, carrying a pin 344 to which is connected one end of a bell crank 346 which is pivoted by the pin 348 to the bracket 350 of the quadrant 258, the other end of the bell crank 346 being connected by the pin 352 to the yoke 354 carried by the rod 356 which is shown broken but which may be prolonged and connected to any form of operating mechanism desired. It will be readily seen that by pulling the rod 356 to the left in Fig. 1 the bell crank pulls the by-pass valve 137 downward, which corresponds to motion of the said valve 137 to the right in Fig. 5, thereby permitting the pipes 122 and 130 to communicate through the by-pass valve chamber 134, thus short-circuiting the two sides of the main fluid circuit. In the plug 145, which closes the left hand end of the by-pass valve chamber 134, and into which the valve stem 144 projects, is a chamber 360 which is connected by the hole 362 with the groove 364 around the plug 145, the said groove being connected to the upper end of the vertical passage 366, the lower end of which is connected to the left hand end of the adjusting valve chamber 187 which through the hole 368 in the pin 370 is thus connected with the interior of the casing 18.

30 Referring to Fig. 3, I have shown on the top cylinder 28 a pin 372 rigidly connected to the said cylinder and projecting slightly beyond the exterior surface thereof and fitting into a longitudinal groove 374 formed in the inside surface of the cross head 36, the object of the said pin and groove being to insure the cross-head 36 being kept in its proper position at all times with respect to the crank element 48 with which its rollers co-act. For simplicity I have omitted showing the said groove and pin in connection with the other cross-heads and cylinders but it is to be understood that where it is desired to use it the same arrangement as shown 40 on the top cylinder may be employed on all.

45 Referring to Fig. 2, it will be seen that I have provided a pipe 484 which connects the pump and motor sides of the casing 18 near the bottom so that any leakage or 50 serve fluid in the motor side of the casing may pass to the pump side without having to rise above the level of the said pipe.

In Fig. 3 it will be readily seen that as the cylinder element 22 revolves, the cylinder ports 82 pass through a cycle of different positions with respect to the main ports 86 and 88 of the valve head 76, and that while at times there are four of the cylinder ports 82 connected to the port 86, and 55 four others connected to the port 88, with one cylinder port 82 just covered by the bridge 90 or the bridge 92, at other times there are five of the cylinder ports 82 connected to the main port 86, with the other 60 four connected to the main port 88, and at 65 four connected to the main port 88, and at

still other times five of the cylinder ports 82 are connected to the main port 88, with the other four connected to the main port 86. It is thus seen that at times fluid pressure in the port 88 acts on an internal circumferential area of the valve chamber 26 equal to the width of the port 88 multiplied by the circumferential length of the said port 88, while at other times the area exposed to pressure is equal to the width of the said port 88 multiplied by a circumferential length of 180 degrees plus one-half the circumferential length of the bridge 90 or the bridge 92, and as the pressure between the valve head 76 and the valve chamber 26 is continually fluctuating, it is impossible to balance the said valve head 76 against displacement due to this fluctuating pressure by the introduction on the opposite side of the valve of fluid pressure extending over a non-fluctuating area. In order to secure a perfect balance of the valve head 76, I provide in the valve chamber 26 two rows of auxiliary ports 382 and 384 respectively, Fig. 2, which for convenience I term "blind ports" and which are arranged in pairs diametrically opposite each cylinder port 82, the circumferential length of each of the blind ports being equal to the circumferential length of the cylinder port 82 and the width of each of said blind ports being one-half the width of its diametrically opposite cylinder port 82, so that the combined width of each pair of blind ports equals the width of one of the cylinder ports 82, the said blind ports 382 being placed in line with the balance ports 94 and 102, and the blind ports 384 in line with the balance ports 96 and 104, so that the pair of balance ports, for example, the balance ports 94 and 96, will go through the same cycle of operation with reference to the blind ports 382 and 384 that the main port 88 goes through with reference to the cylinder ports 82, and while the force tending to displace the valve head 76 due to fluid pressure between the port 88 and the valve chamber 26 fluctuates, the counterbalancing force on the other side of the valve head 76 fluctuates both in extent and direction in exact synchronism 105 with the said displacement force, thus maintaining the valve in perfect balance at all periods of the cycle, the fluid pressure for causing this counterbalancing effect being introduced into the blind ports 382 and 384, 110 respectively, from the balance ports 94 and 96, respectively, into which the said fluid pressure has been brought from the port 88, by means of the passages 98 and 100 respectively.

115 Similarly, the motor valve chamber 27 is provided with the row of blind ports 383 in line with the balance ports 95 and 103, and the row of blind ports 385 in line with the balance ports 97 and 105, thereby effect- 120 125 130

ing the balancing of the motor valve head 77. The arrangement of the blind ports is more clearly shown in Fig. 4, which is a section through the row of blind ports 383. In effecting this result the shape of the cylinder ports 82 and of the main ports, balance ports and blind ports may be anything desired so long as proper precaution is taken to see that the two balance ports in contacting with the blind ports at all times give the same internal circumferential area exposed to balancing pressure as the area tending to cause displacement due to the main port 88 and the co-acting cylinder ports 82. I find in practice that such a result is most easily obtained by making the contour of the main ports and the cylinder ports and also the balance ports and the blind ports rectangular. This avoids any difficulty in the shaping of the ends of the ports so as to give equal areas, such as is experienced with ports having ends other than rectangular.

In the above description of the means by which the valve head 76 is balanced, I have stated that the balance ports interacting with the blind ports counteract the displacing action of the fluid pressure between the main ports and the co-acting cylinder ports, thus keeping the valve head 76 in balance. I find, however, in practice that there is always a certain amount of fluid pressure which leaks between the valve head and the valve chamber. On one side of the valve head this fluid pressure comes from the main port and the cylinder port, and on the opposite side it comes from the balance ports and the blind ports, the fluid pressure coming from these different ports distributing itself between the surface of the valve head and the internal surface of the valve chamber; the pressure existing in such fluid leakage at any point depending on the distance between the said point and the edge of the port from which the said fluid leaked, and being, of course, less the greater the distance the said point is from the port from which it came. In practice I have also found that the resultant pressure due to such fluid pressure leaking over the surface of the valve head depends to a large extent on the perimeter of the ports from which it distributes, and in balancing the effect of fluid pressure leaking from the main ports and the cylinder ports, by fluid pressure leaking from the balance ports and the blind ports, I find it advantageous to surround the main ports by guard grooves so that the area inclosed by the said guard grooves is equal to or greater than the area inclosed by the guard grooves surrounding the balance ports, the total perimeter on which is greater. I have, therefore, shown in Fig. 2 the valve head 76 provided with guard

grooves 386 and 388 which are cut into the

surface of the said valve head and extend entirely around it, the said guard grooves 386 and 388 being so placed with reference to the cylinder ports and blind ports that the distance between the guard groove and the edge of the main ports is twice the distance between the guard groove and the edge of the balance ports. On the opposite side of the balance ports the diameter of the valve is reduced at a point so positioned that the distance from this edge of the valve head to the nearest edge of the balance ports is the same as the distance from the other edge of the balance ports to the guard groove. In order that any fluid pressure leaking from the main ports 86 or 88 to the guard groove 388, or from the balance ports 96 or 104 to the said guard groove, may be carried away therefrom, I provide a radial hole 390 which leads inwardly through the said guard groove to meet the axial hole 392 formed in the said valve head, the said axial hole 392 opening at its outer end so that any fluid pressure coming thereto may pass on out into the space between the valve head 76 and the driving head 68 and from thence through the hole 394 into the interior of the casing 18. Similarly, the guard groove 386, on the other side of the main ports, is provided with a radial hole 396 connected with the axial hole 398 which in turn connects with the radial hole 400, so that any pressure in the said guard groove may pass therefrom into the interior of the casing 18.

Similarly the valve head 77 is provided with the guard groove 387, radial hole 391, axial hole 393 and hole 395 in the driving head 69, and the guard groove 389, radial hole 397, axial hole 399 and radial hole 401, so that fluid pressure coming into the said guard grooves may be free to pass into the interior of the casing 18.

While the valve element 74 is thus balanced in the valve chambers against displacement therein due to the fluid pressure acting on it, by means of equal and opposite fluid pressure introduced on the opposite side of the valve, yet I find in practice that owing to the action of gravity and other causes, the valve element at times may get slightly out of center with respect to the valve chamber, and while the eccentricity is very small, since the clearance between the valve element and the valve chamber is only a very small fraction of an inch, yet any amount of eccentricity tends to permit fluid pressure to leak more readily on one side of the circumference of the valve than on the other, thus causing a slight unbalancing action, which of itself tends to still further increase the eccentricity until the valve may be forced heavily against one side of the chamber, preventing any leakage on that side and increasing the leakage on the other

side. In order to obviate this action which cannot occur so long as the valve element is concentric with the valve chamber, I provide the valve element 74 with the hub 560, which projects from the left hand end of the valve head 76, and interposed between the said hub 560 and the interior of the valve chamber 26 is a bearing 562, and from experience I have found it advantageous to make this bearing of the ball or roller type as such a type permits freedom of rotation with practically no radial play. Similarly on the motor end of the valve element is a hub 561 projecting from the right hand end of the valve head 77 and interposed between the said hub and the interior of the motor valve chamber 27 is the ball bearing 563. The valve element 74 is thus held concentric at one end with the pump valve chamber 20 and at the other end with the motor valve chamber, the gimbal rings 79 and 80 and their co-acting pins holding the valve against rotation, but at the same time permitting freedom of radial adjustment, all 25 of which has been previously described, thus allowing the valve element 74 to be truly in line with the valve chamber of the pump and the valve chamber of the motor, and at the same time insuring that the bridges separating the ingress and egress ports are held truly in line with the line passing through the centers of the rotary cylinder elements and the centers of their respective crank elements.

35 In order to obtain a high percentage of efficiency in power transmission, as well as to keep the size and weight of the device as small as possible, it is necessary to use very high pressures in the working fluid in the main fluid circuits. When such high pressures are used the stresses on the material at times become exceedingly high. Furthermore, with such high pressures the clearances between the working joints of the 40 valve heads and valve chambers must be exceedingly small to prevent undue leakage of the working fluid. It is therefore necessary that the valve heads should be prevented from becoming distorted under the heavy 45 stresses to which they are subjected by the high pressure fluid. The stresses to which the valve heads are subjected are not only radial in direction but there are also axial stresses, and the final or resultant strains 50 produced thereby result in the valve heads becoming seriously bent and distorted unless the bending forces acting in one direction are neutralized or practically neutralized by bending forces acting in the opposite direction.

55 Referring now to Figs. 2 and 3, high pressure fluid in the port 88 and passages 85 produces an axial stress on the valve head 76 which is eccentric to the center of gravity of 60 the holding section of the material and, there-

fore, produces a bending moment which is measured by the distance of the center of pressure of the fluid, multiplied by the pressure, multiplied by the area of the section under pressure. On the other hand the high 70 pressure fluid in the port 88 also acts radially in the said port to produce a slight bending moment in the opposite direction, while the high pressure fluid in the balance ports 94 and 96 also produces a bending moment opposite to that produced by the axial pressure, and the high pressure leakage fluid from the balance ports and from the main port 88 also produce bending moments acting on the valve head. I therefore, so proportion and position the balance ports and the leakage surfaces that the bending moments due to the fluid pressure acting therein and thereon will neutralize or partially neutralize the bending moments due to the 80 fluid pressure in the main ports and on the leakage surfaces therefrom, the section of the valve which is subjected to axial pressure being, of course, likewise proportioned and positioned so as to readily permit such 85 a balancing of bending moments. I find such a balancing of the bending forces on the valve head of the greatest practical importance, as without such balancing the valve head is distorted under high pressures to 90 such an extent as to greatly reduce the efficiency of the machine and increase the wear of the parts.

95 While there are many materials which may be employed in the constructions of the pump and motor here shown, and while I do not limit myself to any particular material for any part, yet I have found by extended and costly experiments that unusually good results as regard reliability, freedom from cutting or galling, efficiency and durability are secured by making the valve element of cast iron, the cylinder element of cast iron, the pistons of cast iron, the cross heads of hardened steel, so that the 100 cross-head pins may be formed integral therewith and will form suitable races for the hardened steel balls working thereon, the rollers of hardened steel for the same latter reason, and the track whereon the rollers operate also of hardened steel, not only to minimize wear, but also since such a track of steel which has been rendered sufficiently hard to prevent the undulatory wave action 105 of the material as the rollers pass over it (such a wave action as is well known in connection with the passage of a locomotive over a railroad track), gives the mechanism a much higher percentage of efficiency. As the advantages of such combination of materials have been developed only after extended experiments, and I have been unable to find any published information to guide me in such experiments, I shall claim the 110 same.

Referring to Fig. 1, it will be seen that the casing 18 terminates at the right hand end in a spherical hub 73, which is mounted in a spherical socket 376, which is supposed to be connected to a suitable frame-work by which the mechanism is supported. Surrounding the two supporting arms 56 and 60 are cylindrical sockets 378 and 380 respectively, which are also supposed to be connected to the same supporting framework. The spherical socket and the two cylindrical sockets may be the only means of support of the casing 18 and consequently of the entire mechanism, and when such is the case, the mechanism is given a three point support thus permitting the framework which supports the said mechanism to be considerably warped or twisted without in any way straining the mechanism itself. I find from practice that this is not only desirable but practically necessary in some uses of the mechanism.

Referring now more particularly to Figs. 13 to 16, I have there shown a mechanism in which the pump is a practical duplicate of the pump shown in the previous figures, but in which the motor instead of being provided with a fixed length of stroke is made a practical duplicate of the pump, thereby providing it with an adjustable stroke whereby a greater range in the relative speeds of the pump and the motor may be obtained. In the mechanism shown in Figs. 1 to 12 the range of relative speeds of the pump and motor for one direction of revolution of the motor varies from the maximum speed of the motor, determined by the ratio of the maximum stroke of the pump to the fixed stroke of the motor, down to zero when the pump stroke is $\frac{1}{2}$. In the mechanism shown in Figs. 13 to 16 the theoretical range of speed of the motor, in one direction, compared with that of the pump is from infinity to zero, and, while in practice such a range is not only not necessary, but not attainable, yet the provision of the motor with an adjustable stroke does in practice permit the motor stroke being reduced to a fraction (for example, $\frac{1}{2}$ or $\frac{1}{4}$ its maximum stroke) thereby increasing the range of relative speeds three or four times. The adjustment of the stroke of the motor may be effected by fluid pressure through a control valve block similar to the control valve block 127 of the pump, in conjunction with fluid pressure utilizing means in the adjusting heads and adjusting chambers of the motor similar to the corresponding parts, previously described, of the pump. Since, however, the adjustment of the stroke of the motor is in general less frequent than that of the pump, and may, if desired, be always effected when there is no fluid pressure in the mechanism, by reducing the pump stroke to zero and thereby removing any resistance

to manually adjusting the motor stroke, I prefer in practice to simplify the mechanism by performing the adjustment of the motor stroke by manual exertion by the means which I will now describe.

Extending from one of the adjusting heads of the motor crank element 49 is a rod 403 which in Fig. 13 is shown as passing through the arm 57 to the exterior. Formed on the said rod 403 are screw threads 405 co-acting with threads in the bore of the bevel gear 415 held between the shoulders 409 and 411 of the bracket 413 fastened to the end of the arm 57. The bevel gear 415 co-acts with the bevel gear 417 journaled in the arm 419 formed on the bracket 413. Connected to the said gear 417 is a rod 421 on the other end of which is a wheel 423 by means of which the operator may rotate the said gear 417 and through it the bevel gear 415 in either direction and thereby force the rod 403 to adjust the motor crank element 49 to any desired extent in either direction.

In the longitudinal sectional view, Fig. 14, through the mechanism comprising the adjustable stroke pump and the adjustable stroke motor, I have provided on the inner side of the driving head 68, of the pump driving shaft 70, the driving dogs 424 which co-act with the pin 426 of the shaft 428 which terminates on its left hand end in a plunger 430 which is slidably mounted in the chamber 432 formed in the driving shaft 70. The said connecting shaft 428 passes freely through the hole 434 in the center of the valve element 74 and terminates at its other end in a plunger 431 which is slidably and rotatably mounted in the chamber 433 formed in the motor driving shaft 71. Formed on the inner side of the motor driving head 69 are driving dogs 425 which, with the parts in the positions shown in Fig. 14, are just out of contact with the driving pin 427 on the shaft 428, so that under these conditions the connecting shaft 428 may freely rotate with the pump driving head 68 without in any way affecting the motor driving head 69. Formed in the plunger 431, on the right hand end of the connecting shaft 428, is a recess 435 in which is a compression spring 437 which reacts between the said connecting shaft 428 and the motor driving shaft 71, thus keeping the connecting shaft 428 forced toward the left or pump side of the mechanism. Formed on the hub 72, on the left hand end of the casing 18, is a 3-way valve chamber 440 in which is rotatably mounted a 3-way valve 442, and connected to the said valve 442 is a lever 444 by which it may be rotated. Formed in the upper side of the 3-way valve chamber 440 is a passage 446 to which is connected a pipe 448, which is shown in Figs. 13 and 15 as connected at its 130

other end with the leakage supply pipe 201 from the leakage pump 280, whereby fluid pressure from the said leakage pump is always connected to the said passage 446. Formed in the lower side of the valve chamber 440 is a passage 450 which terminates at its lower end in a groove 452 formed in the bore of the hub 72. Formed in the pump driving shaft 70 is a radial hole 454 which connects with the axial hole 456, the other end of which terminates in the chamber 432 formed in the end of the said pump driving shaft, whereby, when the 3-way valve is rotated 90 degrees in the direction of the arrow in Figs. 14 and 15 from the position there shown, fluid pressure may pass from the leakage pump 280, through the pipe 448 and valve chamber 440, into the chamber 432, where acting against the plunger 430 it may force the connecting shaft 428 toward the right, thus causing the pin 427 to co-act with the driving dogs 425 of the motor driving head 69, and thereby driving the motor by direct mechanical connection with the pump. When the 3-way valve 442 is in the position shown in Figs. 14 and 15 fluid pressure from the pipe 448 is cut off from the chamber 432, which will then be connected with the passage 458 formed in the rear side of the 3-way valve chamber 440, Fig. 14, the said passage making a right angle bend as shown in Fig. 13 and connecting at its other end with the interior of the casing 18, and thereby permitting any fluid pressure in the chamber 432 to pass therefrom into the said casing 18, thus allowing the spring 437 at the other end of the connecting shaft 428 to force it toward the left so that the pin 427 ceases to co-act with the driving dogs 425 of the motor driving head 69. Such mechanical connection between the pump and motor will in general not be made except when the capacity of the pump and the capacity of the motor have by adjustment been made equal, so that the motor has been brought by the fluid pressure to practically the same speed as the pump. The provision of mechanical connecting means makes it possible to reduce the power losses in the mechanism when it is desired to drive the motor at the same speed as the pump, since such mechanical connection as soon as established relieves the pump of all fluid pressure necessary for driving the motor, and though the fluid is still circulated between the pump and the motor, unless both have been adjusted to zero stroke, it is without pressure, thus reducing the pressure on the various bearings. Furthermore when the said mechanical connection is established, the by-pass valve 137 may be opened so that any slight difference in capacity of the pump and motor will not tend to create pressure on either side of the fluid circuit of the mechanism. Furthermore, should any damage occur to either the

pump or the motor, whereby it is impossible to maintain fluid pressure in the fluid circuits of the mechanism, the direct mechanical connection between the pump and the motor can, if desired, be established to enable the pump to drive the motor. 70

While the direct mechanical connection of the pump and motor may be effected as above described by direct manual operation of the lever 444 of the 3-way valve 442, yet 75 I prefer to accomplish it by the means which I will now describe. Referring again to Figs. 13 to 16, the lever 444 of the 3-way valve is provided at its upper end with a hole 460 through which a pin 462 connects 80 it to the yoke 464 on the end of the rod 466, which terminates at its other end in a yoke 468, by which it is connected to the upper end of the arm 470 which in turn is pivoted to the bracket 472 formed on the quadrant bracket 270. Connected to the arm 470 is a tension spring 474, which is fastened at its other end to the quadrant 258, thus acting to normally keep the 3-way valve in the position shown in Figs. 13 to 15. The position of the arm 470 is so chosen that when the handle of the control lever 250 is moved upward in Fig. 13, and to the left in Fig. 15, to the position where the stroke of the pump has been made equal to the maximum 95 stroke of the motor, and the pump and motor are revolving at equal speeds in the same direction, the lever 250 will contact with the arm 470 and further movement of the control lever in the same direction will 100 force the arm 470 to rock the 3-way valve lever 444 and thus permit fluid from the pipe 201 to operate the connecting shaft 428, and thus enable the pump to drive the motor by the direct mechanical connection as previously described. 105

In Figs. 13 to 15, I have shown a still further improved method of supporting the mechanism. The hub 73 in which the casing terminates at the right hand end of Fig. 14 110 is made cylindrical instead of spherical, as in Fig. 2, and is surrounded by a bushing or sleeve 481 which is free to slide thereon, the said bushing having a spherical outer surface whereby it fits in the spherical socket of the supporting bracket 376 shown in Fig. 13. Similarly the supporting arm 56, in which the upper side of the pump half of the casing 18 terminates in Fig. 13, is provided with a spherical bushing or sleeve 115 480 which is free to slide thereon, the said bushing fitting in the spherical socket of the supporting bracket 380. The opposite supporting arm 60 of the pump half of the casing is provided with a spherical surface 120 formed integral therewith or by a bushing secured thereto, the said spherical surface of the arm 60 fitting in the spherical socket of the supporting bracket 378. By this means the mechanism is so supported that 125

the driving shaft 70 is held at a definite distance from the supporting bracket 378 but the possibilities of the casing 18 being strained by warping of the supporting frame to which the supporting brackets are attached is reduced to the minimum. This is especially important where the mechanism is used on motor vehicles or like machines.

In Figs. 17, 18 and 19, I have shown improvements in details of construction of certain parts which for clearness of explanation were shown in a simpler form in the views of the complete mechanism. In Fig. 17 the cylinder 28 is jacketed with a hardened steel shell 520 fitting tightly on the exterior wall thereof. Interposed between the said jacket and the interior wall of the cross head 34 is a bushing 521 acting as a retaining sleeve for the balls 522, thus providing means for substituting rolling friction for the sliding friction which occurs when the cross-head slides directly on the outer surface of the cylinder, as in Fig. 2. The bushing 521 is provided with an upper shoulder 523 which prevents the upper end from moving farther in on the cylinder 28 than the upper end thereof, and also a lower shoulder 524 which prevents the lower end from moving farther into the cross head than the lower end thereof. To prevent the cross head 34 from turning around on the jacket 520, one row of balls, such as 526, Fig. 18, are made slightly larger than the other balls 522, the said balls 526 fitting into the longitudinal groove 527 formed in the jacket 520 and also into the groove 528 formed in the cross head 34, the latter being clearly shown in the enlarged partial section of the cross head in Fig. 19. I have also shown in Figs. 17, 18 and 19 how the cross head pins 38 and the rollers 42 may be both formed with grooved ball tracks 530 and 531 respectively, the outer lips 532 and 533 respectively, of which co-act with the balls 40 to retain the said rollers 42 in their proper position on the said cross head pins 38, thus dispensing with the rivets 44 shown in Fig. 2, and thus reducing the frictional resistance of the said rollers.

The operation of the device is as follows: Assuming all the ports and passages to be filled with fluid and an extra amount of fluid to be in the casing 18, and the driving shaft 70 of the pump to be driven by some external power in a clockwise direction as viewed from the left in Fig. 1 and all the parts to be in the positions shown in Figs. 1 to 12, it will be seen from the sectional view in Fig. 3 that all of the pistons 30 in the cylinders 28 that are above the horizontal median line are drawing in fluid through their cylinder ports 82 and the main ingress port 86 from the ingress passages 84, while all of the cylinders that are below the horizontal median line are forcing fluid out into

the egress passages 85. From the sectional view, Fig. 4, it will be seen that the fluid pressure in the passages 85 will enter such of the motor cylinders 29 as are below the horizontal median line, thereby causing the rollers 43 to be forced against the tracks 63, which being eccentric to the center of rotation of the motor cylinders causes the motor cylinder element 23 to be revolved in a clockwise direction as viewed in Fig. 4, 75 which is a counter-clockwise direction when viewed from the left hand end of Fig. 1, and therefore, the motor shaft 71 will be driven in an opposite direction from the direction of rotation of the pump shaft 70. 80 As the motor cylinders revolve, the cylinders which are above the horizontal median line in Fig. 4 will exhaust their fluid into the passages 84, thus supplying the said passages 84 with fluid to be again sucked up by the pump and delivered by the same to the egress passages 85 under pressure, practically the same amount of fluid being returned from the motor to the pump as is being sent by the pump to the motor at any 90 particular moment. With the eccentricity of the pump crank element 48 adjusted to its extreme right hand position, as shown in Fig. 3, the motor is driven at its highest speed. If the eccentricity of the pump 95 crank element 48 be decreased from this maximum amount, the speed of the motor will be also decreased in exact proportion to the decrease in eccentricity of the pump crank element, so that when the pump crank 100 element is adjusted to the position where its center is coincident with the center of rotation of the pump cylinders the pistons 30 will not reciprocate in the cylinders 28, and consequently no fluid will be sent to the motor which will remain stationary no matter what the speed of rotation of the pump cylinder element is. If the pump crank element 48 be adjusted from its zero position to some position on the other side of 105 the said zero point, the pump cylinders 28 will do their pumping while they are rotating above the horizontal median line and will draw in fluid when they are rotating below the said line, and consequently, fluid 110 under pressure will be delivered to the passages 84, and will pass therethrough to the motor cylinders where it will cause the motor cylinder element 23 to be driven in a direction opposite to that in which it was formerly driven, which is clockwise, as viewed from the left hand end of Fig. 1, which is the same direction of rotation as has been supposed for the pump. As the motor cylinder element thus rotates, the motor cylinders 115 120 will return fluid through the passages 85 back to the pump, the fluid thus circulating in a closed fluid circuit between the pump and the motor. Since the speed of rotation of the motor cylinder element in 125 130

5 this latter direction is dependent on the eccentricity of the pump crank element, and since in Fig. 3 it will be seen that I have provided for sufficient adjustment on the left hand side of the vertical median line to enable the pump crank element 48 to be adjusted as far on this side of the said vertical line as on the other side, such adjustment of the pump crank element from the 10 maximum position of eccentricity on one side of the vertical line to the corresponding position on the other side will cause the motor cylinder element to be driven at all speeds between a maximum in one direction 15 through zero to a maximum in the reverse direction.

In effecting such adjustment of the pump crank element, the operator's handle of the control lever 250, will be pushed upward in 20 Fig. 1, and the said lever acting on the pin 252 as a fulcrum will cause the adjusting valve to be drawn downward in the said figure, which is the same as motion to the right in Fig. 5. Such motion of the adjusting 25 valve causes the valve head 190 to uncover the port 202, permitting fluid pressure derived from the main fluid circuit to pass through the pipe 203 into the space between the piston 221 and shell 216 at the right 30 hand end of Fig. 3, thus causing the crank element 48 to be forced to the left toward its position of concentricity to an extent dependent on the extent of motion given to the control lever 250 by the operator. When 35 the pump crank element 48 has been adjusted to the position of concentricity with the rotating pump cylinder element 22, if the operator desires to pass through the center to the opposite side, he must exert sufficient 40 force on the control lever 250 to cause the cross-head 196 at the end of the adjusting valve to be brought against the nuts 274 when further force applied to the control lever by the operator, and in the same direction, will cause the lever to act on the pin 45 266 as a fulcrum, whereby the pump crank element 48 will be manually forced out of its position of concentricity to the left of the vertical median line in Fig. 3, thereby 50 causing fluid pressure to be generated and delivered to the passages 84 whence such pressure is free to pass through the by-pass valve chamber, high pressure valve chamber and the connections thereto heretofore 55 scribed, to the high pressure chamber of the adjusting valve, where the valve head 190 has uncovered the port 202, and fluid pressure will then pass through the pipe 203 to the space between the piston 221 and shell 60 216 and cause the pump crank element 48 to be adjusted still farther to the left in Fig. 3 without further manual exertion, and to an extent dependent on the extent of motion of the control lever by the operator, 65 thus causing the motor to rotate in this

opposite direction at any desired speed. In order to cause the pump crank element 48 to be returned to its position on the other side of the vertical median line as shown in Fig. 3, it is only necessary for the operator 70 to move the control lever 250 downward in Fig. 1, thus causing the adjusting valve head 191 in Fig. 5 to uncover the port 204, thus permitting fluid pressure to pass through the pipe 205 to the space between 75 the piston 234 and the shell 233, where it will force the crank element 48 toward the right in Fig. 3 until the said crank element arrives at its position of concentricity, if the operator has continued to move his control 80 lever downward as the crank element moves in order to keep the port 204 uncovered by the adjusting valve head 191. When the pump crank element 48 reaches the position of concentricity it must be carried through 85 this zero position where there is no fluid pressure, and the motor is consequently stationary, by means of manual force exerted on the adjusting lever 250, and if such manual force be exerted in a downward direction on the handle of the said lever, as viewed in Fig. 1, the cross head 196 will be forced upward until its ears 272 abut against the shoulders 278 of the studs 276. The pin 266 in the right hand end of the control 95 lever 250 then becomes the fulcrum, and such manual force on the lever 250 if continued will cause the pump crank element 48 to be forced toward the right of the vertical median line in Fig. 3, thereby causing 100 fluid pressure to be delivered to the passages 85, from whence it will pass into the high pressure section of the adjusting valve chamber in Fig. 5, and from thence through the pipe 205 to act against the adjusting head 105 50, in Fig. 3, and thereby cause further adjustment of the crank element 48 toward the right, unless the operator has moved the handle of the control lever upward in Fig. 1 sufficiently to cause the adjusting valve 110 head 191 to again cover the port 204.

Since the leakage pump 280 is always driven whenever the pump driving shaft 70 is rotated, it will draw fluid from the bottom of the casing 18 and force it through 115 the pipe 201 into the low pressure section of the adjusting valve chamber, from whence it is free to pass by means of the passages and valves heretofore described to low pressure or suction side of the main 120 fluid circuit. Such fluid drawn from the casing 18 before entering the pipe 201 passes through the low pressure relief valve chamber 312, and if the various working joints of the mechanism leak fluid as rapidly as the 125 leakage pump draws it from the casing 18, all of it will be delivered to the low pressure or suction side of the main fluid circuit.

When, however, the various leakages from the main circuits into the casing are not as 130

great as the amount of fluid drawn from the casing by the leakage pump, such excess fluid delivered to the low pressure side of the main circuit will raise a pressure in this 5 chamber until the pressure so generated by the leakage pump is sufficient to cause the low pressure relief valve 328 to be forced open so that such excess fluid will pass into the interior of the casing, a constant back 10 pressure thereby being maintained in the low pressure or suction side of the main fluid circuit, the extent of the back pressure being dependent on the stiffness of the springs of the low pressure relief valve. In 15 practice I have found that the extent of back pressure which it is desirable to maintain is dependent on the speed of rotation of the mechanism, the back pressure being maintained slightly higher the higher the 20 speed, whereby cavitation in the pump is prevented.

It is to be understood that I do not limit myself to the combination of a pump and motor which are in line with each other or 25 where both are inclosed in a single casing, as the motor may be at any distance from, and in any position with reference to the pump, and the valve element of each may be separated and distinct from that of the 30 other and the fluid connection between them, established by suitable pipes. I further do not limit myself to any particular number or size of cylinders in the pump or the motor or to an equidistant spacing of them, and 35 the pump and the motor may have the same or a different number of cylinders.

While I have shown the preferred embodiment of my invention in the drawings, it is to be distinctly understood that I do 40 not limit myself to the particular form of the different elements or the specific combinations thereof, as it is evident they may be all varied by substitution of mechanical equivalents and other elements, adapted to 45 perform the functions set forth, without departing from the spirit or scope of my invention, as hereinafter set forth in the claims.

What I claim is:

1. In a variable speed gear, the combination 50 of a pump, a motor, and a valve element through which fluid may pass from the said pump to the said motor, said valve element being fixed relatively to the said pump and motor as regards rotation but 55 freely movable radially.

2. In a variable speed gear, the combination 60 of a rotary cylinder pump, a motor, and a valve element through which fluid may pass from the said pump to the said motor, said valve element being fixed relatively to the said pump and motor as regards rotation, but freely movable radially.

3. In a variable speed gear, the combination 65 of a rotary cylinder pump, a rotary cylinder motor, and a valve element through

which fluid may pass from the said pump to the said motor, said valve element being fixed relatively to the said pump and motor as regards rotation, but freely movable radially. 70

4. In a variable speed gear, the combination 75 of a rotary radial cylinder pump, a motor, and a valve element through which fluid may pass from the said pump to the said motor, said valve element being fixed relatively to the said pump and motor as regards rotation, but freely movable radially.

5. In a variable speed gear, the combination 80 of a rotary radial cylinder pump, a rotary cylinder motor, and a valve element through which fluid may pass from the said pump to the said motor, said valve element being fixed relatively to the said pump and motor as regards rotation, but freely movable radially. 85

6. In a variable speed gear, the combination 90 of a rotary radial cylinder pump, a rotary radial cylinder motor and a valve element through which fluid may pass from the said pump to the said motor, said valve element being fixed relatively to the said pump and motor as regard rotation, but freely movable radially. 95

7. In a variable speed gear, comprising a pump, and a motor, the combination with an 100 inclosing casing, of a valve element through which fluid may pass from the said pump to the said motor, said valve element being radially free with respect to said casing but relatively fixed thereto against rotation. 100

8. In a variable speed gear, comprising a 105 rotary cylinder pump, and a motor, the combination with an inclosing casing of a valve element through which fluid may pass from the said pump to the said motor, said valve element being radially free with respect to said casing but relatively fixed thereto against rotation. 105

9. In a variable speed gear, comprising a 110 rotary cylinder pump, and a rotary cylinder motor, the combination with an inclosing casing of a valve element through which fluid may pass from the said pump to the said motor, said valve element being radially free with respect to said casing but relatively fixed thereto against rotation. 110

10. In a variable speed gear, comprising a 115 rotary radial cylinder pump and a motor, the combination with an inclosing casing of a valve element through which fluid may pass from the said pump to the said motor, said valve element being radially free with respect to said casing but relatively fixed thereto against rotation. 120

11. In a variable speed gear, comprising 125 a rotary radial cylinder pump and a rotary cylinder motor, the combination with an inclosing casing of a valve element through which fluid may pass from the said pump to the said motor, said valve element being 130

- radially free with respect to said casing but relatively fixed thereto against rotation.
12. In a variable speed gear comprising a rotary radial cylinder pump, and a rotary radial cylinder motor, the combination with an inclosing casing of a valve element through which fluid may pass from the said pump to the said motor, said valve element being radially free with respect to said casing but relatively fixed thereto against rotation.
13. In a variable speed gear, the combination of a pump comprising cylinders radiating from a common center, a motor and a valve element extending from the said common center of the pump cylinders to the motor and through which a fluid may pass to connect the said pump to the said motor.
14. In a variable speed gear, the combination of a pump comprising rotary cylinders radiating from a common center, a motor and a valve element extending from the said common center of the pump cylinders to the motor and through which a fluid may pass to connect the said pump to the said motor.
15. In a variable speed gear, the combination of a pump comprising cylinders radiating from a common center about which they rotate, a motor comprising cylinders radiating from a common center, and a valve element extending from the said common center of the pump cylinders to the said common center of the motor cylinders.
16. In a variable speed gear, the combination of a pump comprising cylinders radiating from a common center about which they rotate, a motor comprising cylinders radiating from a common center about which they rotate, and a valve element extending from the said common center of the pump cylinders to the said common center of the motor cylinders.
17. In a variable speed gear, the combination of a rotary radial cylinder pump, a rotary radial cylinder motor and a stationary valve element extending from the center of rotation of the pump cylinders to the center of rotation of the motor cylinders.
18. In a variable speed gear, the combination of a rotary radial cylinder pump, a rotary radial cylinder motor, and a single valve element extending from the center of rotation of the pump to the center of rotation of the motor and acting as a valve for the pump and as a valve for the motor.
19. In a variable speed gear, the combination of a pump element provided with a central valve chamber and having multiple, radially arranged cylinders, a stationary valve element located in the said valve chamber at the center from which the said cylinders radiate and about which they rotate, and a motor driven by fluid pressure generated in the said pump.
20. In a variable speed gear, the combination of a pump element provided with a central valve chamber and having multiple, radially arranged cylinders, and a stationary valve element located in the said valve chamber and about which the said cylinders and valve chamber revolve, and a motor similarly constructed and driven by fluid pressure generated in the said pump.
21. In a variable speed gear, the combination of a pump element provided with a central valve chamber and having multiple, radially arranged cylinders, and a stationary valve element located in the said valve chamber and about which the said cylinders and valve chamber rotate, and a motor similarly constructed and driven by fluid pressure generated in the said pump, the said valve element of the pump and the valve element of the motor constituting a unitary structure.
22. In a variable speed gear, the combination of a pump element provided with a central valve chamber and having multiple, radially arranged cylinders, and a stationary valve element located in the said valve chamber and about which the said cylinders and valve chamber rotate, a motor similarly constructed and driven by fluid pressure generated in the said pump, and means whereby the said valve element may be balanced by the said fluid pressure.
23. In a variable speed gear, the combination of a pump embodying an element provided with a central valve chamber and having multiple, radially arranged cylinders, and a motor similarly constructed and driven by fluid pressure generated in the said pump.
24. In a variable speed gear, the combination of a pump comprising multiple cylinders radiating from a common center with means for varying its capacity, a motor, and a valve element extending from the common center of radiation of the pump cylinders to the motor and through which a fluid may pass to connect the said pump and motor.
25. In a variable speed gear, the combination of a rotary radial cylinder pump with means for varying its capacity, a rotary radial cylinder motor and a stationary valve element extending from the center of rotation of the pump to the center of rotation of the motor cylinders.
26. In a variable speed gear, the combination of a rotary radial cylinder pump with means for varying its capacity, a rotary radial cylinder motor with means for varying its capacity and a stationary valve element extending from the center of radiation of the pump cylinders to the center of radiation of the motor cylinders.
27. In a variable speed gear, the combination of a multiple cylinder pump embody-

ing a single valve element which is balanced for direct fluid pressure and also for indirect leakage pressure, and a motor driven by fluid pressure from the pump.

28. In a variable speed gear, the combination of a multiple cylinder pump, a multiple cylinder motor, and a single valve element acting as a valve both for the pump and the motor, said valve element being balanced for direct fluid pressure and also for indirect leakage pressure.

29. In a variable speed gear, the combination with a motor, of a multiple cylinder pump embodying a valve chamber and a valve element, said valve element comprising main ingress and egress ports for the passage of fluid to and from the pump respectively, balance ports formed in the surface of said valve element and cross connected to said main ingress and egress ports, and leakage guard grooves adjacent said main ports and said balance ports.

30. In a variable speed gear, the combination with a motor, of a multiple cylinder pump embodying a valve chamber and a valve element, said valve element comprising main ingress and egress ports for the passage of fluid to and from the pump respectively, balance ports formed in the surface of said valve element and cross connected to said main ingress and egress ports, and leakage guard grooves adjacent said main ports and said balance ports, said leakage guard grooves being so arranged that the area of the surface of the said valve element over which fluid pressure may leak from the main ports is substantially equal to the area of the surface of the said valve element over which fluid pressure may leak from the balance ports.

31. In a variable speed gear, the combination with a motor, of a multiple cylinder pump embodying a tubular cylindrical valve casing in the interior of which is mounted a cylindrical valve element, said valve element comprising main ingress and egress ports formed in the peripheral surface of the valve for the passage of fluid to and from the pump respectively, balance ports formed in the peripheral surface of the said valve element and leakage guard grooves between the said main ports and the said balance ports.

32. In a variable speed gear, the combination with a motor, of a multiple cylinder pump embodying a tubular cylindrical valve casing in the interior of which is mounted a cylindrical valve element, said valve element comprising main ingress and egress ports formed in the peripheral surface of the valve for the passage of fluid to and from the pump, respectively, balance ports formed in the peripheral surface of the said valve element and leakage guard grooves between the said main ports and the said balance ports.

alance ports, said leakage guard grooves being so disposed that the area of the surface of the said valve element over which fluid pressure may distribute from the said main ports is substantially equal to the area of the surface of the said valve element over which fluid pressure may distribute from the said balance ports.

33. In a mechanism embodying cylinders grouped around a central tubular cylindrical valve casing and a single cylindrical valve element mounted in said valve casing, acting as a pump or a motor, means for balancing the said valve element as regards direct fluid pressure, and means for balancing the said valve element also as regards indirect leakage pressure.

34. In a mechanism embodying multiple cylinders and a single valve, acting as a pump or a motor, means for balancing said valve as regards direct fluid pressure and means for also balancing said valve as regards indirect leakage pressure.

35. In a mechanism embodying rotary cylinders grouped around a central tubular cylindrical valve casing and a stationary cylindrical valve element mounted in said valve casing, acting as a pump or a motor, a ball or roller bearing between said valve element and valve casing to prevent actual contact between the peripheral surface of the valve element and the surface of the valve casing.

36. In a mechanism embodying rotary cylinders grouped around a central tubular cylindrical valve casing and a stationary cylindrical valve element, provided with main ingress and egress ports for the passage of fluid, mounted in said valve casing, acting as a pump or a motor, provided with balance ports so formed in the said valve element as to balance the valve element with respect to the said valve casing against fluid pressure acting on its main ports, and a ball or roller bearing between the said valve element and the said valve casing to prevent displacement of the valve element in the valve casing.

37. In a variable speed gear, comprising a pump and a motor and a single valve element acting as a valve for both the said pump and the said motor, ball or roller bearings between the said valve element and the said pump, and the said valve element and the said motor, to prevent displacement of the valve element with respect to said pump and said motor.

38. In a variable speed gear, comprising a pump, a motor, an inclosing casing, and a single valve element acting as a valve for both the said pump and the said motor, means for relatively fixing the said valve against rotation with respect to the said casing while leaving it free for radial displacement with respect thereto, and means for

fixing the valve against radial displacement with respect to the said pump and the said motor while leaving it free with respect to rotation of the said pump and the said motor.

39. A mechanism embodying a central cylindrical tubular valve chamber from which radiate multiple cylinders the bores of which are connected at their inner ends by ports to the said valve chamber, a cylindrical valve element mounted in said valve chamber and provided with main ingress and egress ports for fluid in alignment with said cylinder ports, and balance ports provided in said valve element and cross connected to said main ingress and egress ports.

40. A mechanism embodying a central cylindrical tubular valve chamber from which radiate multiple cylinders the bores of which are connected at their inner ends by ports to the said valve chamber, a cylindrical valve element mounted in said valve chamber and provided with main ingress and egress ports for fluid in alignment with said cylinder ports, balance ports provided in said valve element and cross connected to said main ingress and egress ports, and blind ports provided in said valve chamber in alignment with said balance ports and co-acting therewith.

41. A mechanism embodying a central cylindrical tubular valve chamber from which radiate multiple cylinders the bores of which are connected at their inner ends by ports to the said valve chamber, a cylindrical valve element mounted in said valve chamber and provided with main ingress and egress ports for fluid in alignment with said cylinder ports, and means for balancing the said valve element against fluid pressure between it and the wall of the said valve chamber.

42. A mechanism embodying a multiple cylinder element, a valve element provided with ingress and egress ports and acting as a valve for the multiple cylinders, means for generating fluid pressure in the said cylinders, means for balancing said cylinder element and said valve element with respect to each other against the fluid pressure between the said valve ports and the said cylinder element, and means for balancing the said cylinder element and the said valve element with respect to each other against fluid pressure leaking between them.

43. A mechanism embodying a multiple cylinder element, a valve element provided with ingress and egress ports and acting as a valve for the multiple cylinders, means for generating fluid pressure in the said cylinders, means for balancing said cylinder element and said valve element with respect to each other against the fluid pressure between the said valve ports and the said

cylinder element, and means for limiting the area of the valve element and the cylinder element which is exposed to leakage of fluid pressure from said valve ports to substantially equal the area exposed to leakage of fluid pressure from the said balancing means.

44. In a fluid pressure pump or motor a valve element provided with ingress and egress ports, ingress and egress passages and means comprising balance ports for neutralizing the bending stresses on said valve element.

45. In a fluid pressure pump or motor a valve element provided with ingress and egress ports, ingress and egress passages, and means comprising balance ports for creating bending stresses on said valve opposite to the bending stresses arising from fluid pressure in said ingress and egress ports and passages.

46. In a fluid pressure pump or motor a valve element provided with ingress ports and passages, egress ports and passages, balance ports arranged opposite to said ingress ports and having fluid connection therewith and balance ports arranged opposite to said egress ports and having fluid connection therewith.

47. In a fluid pressure pump or motor a valve element provided with ingress ports and passages, egress ports and passages, balance ports, equal in area to said ingress ports, arranged opposite to said ingress ports and having fluid connection therewith and balance ports, equal in area to said egress ports, arranged opposite to said egress ports and having fluid connection therewith.

48. In a fluid pressure pump or motor a valve element provided with ingress and egress ports and passages, ingress and egress balance ports, and limited areas of leakage surface surrounding the ingress port, egress port, and balance ports, so proportioned and disposed that bending stresses on the valve element arising from fluid pressure in the ingress passages and port, and egress balance ports, and over the limited areas of leakage surface surrounding the said ports, are practically counterbalanced by opposite bending stresses arising from fluid pressure in the egress passages and port, and ingress balance ports, and over the limited areas of leakage surface surrounding the said ports.

49. In a pump or motor embodying a casing in which is mounted a non-rotatable crank element capable of bodily adjustment and a rotary element provided with multiple cylinders, the combination of pistons mounted in said cylinders, cross heads mounted on the exterior walls of said cylinders, and rollers journaled on pins on said cross heads and adapted to roll on said

crank element when said rotary cylinder element is rotated.

50. In a pump or motor embodying a rotary multiple cylinder element formed of cast iron, the combination with steel cross heads slidably mounted on the exterior surface of said cylinders, of hardened steel cross head pins formed integral with said cross heads, rollers journaled by balls on the 10 said cross head pins and co-acting with a hardened steel ring, mounted on a relatively fixed but eccentrically adjustable crank element, to cause the said cross heads to slide on the said cylinders when the rollers 15 roll on the said steel ring as the said cylinder element is rotated.

51. In a pump or motor embodying a casing which incloses a multiple cylinder rotary element journaled therein, the combination with a crank element mounted in 20 and supported by said casing and adjustable with respect to the center of rotation of the said multiple cylinder rotary element, from positions on one side of the center of rotation 25 of the cylinder element, to a position where the center of the said crank element practically coincides with the said center of rotation of the cylinder element, means for manually adjusting the said crank element 30 from this latter position to a position where the center of the said crank element is slightly eccentric to the said center of rotation of the cylinder element and power operated means for further adjusting said element. 35

52. In a variable speed gear, the combination of a pump embodying a rotary cylinder element, a motor embodying a rotary cylinder element normally having no mechanical 40 connection with said pump cylinder element, and means for mechanically connecting the said pump cylinder element to the said motor cylinder element when their respective speeds of rotation are approximately 45 equal.

53. In a variable speed gear, the combination of a pump embodying a rotary cylinder element, a motor embodying a rotary cylinder element normally having no mechanical 50 connection with said pump cylinder element, and means for mechanically connecting the said pump cylinder element to the said motor cylinder element when their respective speeds of rotation are approximately 55 equal, and means for actuating the said mechanical connection by fluid pressure.

54. In a variable speed gear, the combination of a pump embodying a rotary element, a motor embodying a rotary element normally having no mechanical connection with said rotary pump element, means for mechanically connecting the said rotary pump element to the said rotary motor element when their respective speeds of rotation are 60 approximately equal, an auxiliary pump 65

and means for actuating the said mechanical connection by fluid pressure derived from said auxiliary pump.

55. In a variable speed gear, comprising a pump and a motor, an inclosing casing 70 from which project three arms whereby said casing may be supported, certain of said arms being partially spherical.

56. In a variable speed gear, comprising a casing in which is inclosed a pump and a 75 motor, two diametrically opposite supporting arms projecting from the sides of the said casing and a third supporting arm projecting from one end of the said casing.

57. In a variable speed gear, the combination with a motor of a pump comprising cylinders arranged at an angle to the axis about which they rotate, a port at the end of each cylinder nearest the axis of rotation, and a valve element provided with ingress 80 and egress ports co-acting with the cylinder ports and through which a fluid may pass to connect the said pump and said motor.

58. In a variable speed gear, the combination with a motor of a pump comprising 85 cylinders arranged around a central valve chamber, ports connecting the cylinders to the valve chamber, and a valve element centrally arranged in the said valve chamber and provided with ports through which a 90 fluid may pass to connect the said pump and said motor.

59. In a variable speed gear, the combination with a motor of a pump comprising cylinders arranged around a central valve 95 chamber, pistons in said cylinders co-operating with a crank element eccentric to and encircling the valve chamber, a valve element co-operating with said valve chamber and a fluid connection through the said 100 valve element from the pump to the motor.

60. In a pump or motor, a cylinder element comprising a valve chamber around which are arranged multiple cylinders, a valve element centrally arranged in said 105 valve chamber, and ball or roller bearings interposed between said valve and the wall of said valve chamber.

61. In a pump or motor, a cylinder element comprising a valve chamber around 110 which are arranged multiple cylinders, a valve element centrally arranged with reference to said valve chamber and co-acting therewith, and means for preventing sliding contact between the surface of the said valve 115 and the surface of the said valve chamber.

62. In a pump or motor, a cylinder, a piston mounted in the bore of the said cylinder, a cross-head mounted on the exterior wall of said cylinder and balls or rollers interposed 120 between the said cross head and the said cylinder.

63. In a pump or motor, a cylinder, a piston mounted in the bore of the said cylinder and having sliding contact between its 125

5 peripheral surface and the internal peripheral surface of the said cylinder, a cross head mounted on the exterior wall of the said cylinder and means for preventing sliding contact between the said cross head and the exterior peripheral surface of the said cylinder when the said cross head is reciprocated with respect thereto.

64. In a pump or motor, a cylinder, a piston 10 mounted in the bore of the said cylinder, a cross head mounted on the exterior wall of the said cylinder, balls or rollers interposed between the said cross head and the said cylinder and means for preventing rotary displacement of the said cross head with reference to said cylinder.

65. In a pump or motor, a cylinder, a pis-

ton mounted to reciprocate in the bore of the said cylinder and having sliding contact therewith, a cross head mounted to reciprocate on the exterior wall of the said cylinder, means for preventing sliding contact between the said cross head and the said cylinder, and means for preventing rotary displacement of the said cross head with reference to said cylinder.

20

In testimony whereof I affix my signature to this specification, in the presence of two subscribing witnesses.

CHARLES MATTHEWS MANLY.
